UNITED STATES PATENT OFFICE.

WILLIAM ASHBEETRITTON, OF LINCOLN, ENGLAND.

ENDLESS MOVING CHAIN TRACK.

1,318,188.

Specification of Letters Patent.

Patented Oct. 7, 1919.

Application filed June 13, 1917. Serial No. 174,564.

To all whom it may concern:

Be it known that I, WILLIAM ASHBEETRITTON, a subject of the King of Great Britain and Ireland, and residing at Wellington Foundry, Firth Road, Lincoln, in the county of Lincoln, England, have invented certain new and useful Improvements in and Relating to Endless Moving Chain Tracks, of which the following is a 10 specification.

This invention relates to transport vehicles and more particularly to those that are propelled by an endless moving chain track or tracks.

15 In such vehicles the load is usually carried by means of rollers mounted in a track, which rollers engage with the back of the lower run or stretch of the chain track.

It has been found when these vehicles are 20 used for traversing rough and broken ground that the lower run of the chain track sags and falls away from the rollers, if used, when passing over a depression in the running surface or when an edge of the track 25 rides along an upstanding curb or ridge or when by other obstacles it has a tendency to become tilted. Under these conditions the track may fail to regain its proper position when level ground is reached, or it may be 30 deformed or broken. Moreover, the load supporting rollers which engage with the back of the track have hitherto been fitted with fixed flanges. In practice it often occurs that the flanges buckle and peel off 35 on the occurrence of strains and stresses due to sluing the machine around, and the track is liable to become laterally displaced.

The object of the present invention is to overcome the defects above referred to.

40 The invention consists in arranging in close proximity to the lower run of the chain track, a rigid extension of the vehicle frame, which extension is adapted to coöperate with the chain track to loosely confine it and 45 prevent the chain track from sagging or dropping away from its proper working position due to abnormal running conditions, the frame extension also serving if desired to prevent lateral displacement of the track. 50 The invention also consists in fitting the 55 load supporting rollers, carried by the rigid frame extension, with flanges adapted to offer a yielding resistance to average stresses, any excessive strains, however being resisted by the frame extension.

The invention will now be described with

reference to the accompanying drawings, in which:—

Figure 1 is a side elevation of a portion of a motor tractor showing the present invention applied thereto.

Figs. 2, 3 and 4 illustrate the chain track in detail and the rollers that coöperate therewith to support the weight of the vehicle, Fig. 2 being a transverse section of the track and showing a pair of rollers in section; Fig. 3 being a plan view of one track link and the rail heads attached thereto; and Fig. 4 being a side view of a portion of the track with one roller in position thereon.

As will be seen in Fig. 1, the moving endless chain track *a* is carried by the main frame *b* of the vehicle upon sprocket wheels *c, d*, of which in the usual way *c* is the driver and *d* the idler. The driver may be actuated through any suitable and usual power transmission from the main shaft *e* of the motor *f* illustrated diagrammatically. The chain tracks, when two are used, are preferably arranged at each side of the vehicle in between a main frame *b* and an auxiliary frame *b'* which stands out from the frame *b* a sufficient distance to accommodate each track. Both of these frames each carry depending webs *g*, one of which is shown in Fig. 1, and are arranged on the respective sides of the chain track and both extend to within a short distance of the ground.

Referring now more particularly to Figs. 90 2, 3 and 4, the chain tracks each comprise a series of tread plates *h* of general rectangular form and having sides of a length preferably greater than the width of the ends. They are flat for the greater part of their 95 area but each has one transverse edge bent down to form a hollow flange or corrugation to form a salient or rib *k* to afford grip upon the road. Such edge is overlapped by that of the succeeding plate, the upper surfaces 100 of the plates being flush. In the transverse direction of the chain the ribbed part of each plate is dished and bent upward at its ends to also improve the grip and facilitate riding over projections in the road. To secure the plates together, there is arranged on the back of each plate and in close proximity to the respective ends, a pair of brackets *l* each comprising a pair of rail heads extending over the whole width of 110 the plate and somewhat beyond. The rail heads are spaced apart at *m* to accommodate

the chain track sprockets *c*, *d*, and at one end they widen to form jaws *n* and at the other end they are reduced to form an extension *o* having a connecting sleeve *p*. The 5 extension end fits between the jaws *n* of the succeeding pair of rail heads of the next tread plate and are secured thereto by a bolt or pin *q* passing through the jaws *n* and sleeve *p*, while the jaw end correspond- 10 ingly embraces the extension end of the preceding pair of rail heads on the adjoining tread plate. About midway of their length the rail heads are connected by a cross web *r*, while *p* constitutes the means by which 15 the chain track is driven through the teeth of the sprocket wheels *c*.

The upper surfaces of the rail head members are flanged both inwardly and outwardly to afford a good bearing surface and 20 are level with one another and smooth to receive the weight supporting rollers *s*, one roller to each line of rail heads. The outwardly extending flange *t* is somewhat wider as shown, its face extending to within a 25 short distance of side frames or webs *g*, for a purpose hereinafter specified. These webs *g*, as before stated, are attached to the main and auxiliary frames *b*, *b'* of the vehicle, the webs *g* together constituting an exten- 30 sion of the vehicle framing.

The rollers *s* are mounted in pairs on sleeves surrounding the spindles *u*, both extremities of which are carried by, and secured in any suitable way in bearings in 35 the respective side frames or webs *g*. As will be seen more particularly in Fig. 1, the lower part of the vehicle is supported by the series of rollers *s*, as shown, some of the rollers being plain and the others flanged 40 as will now be described, or they may all be flanged. The lower edges of the webs *g* are fitted with inner and outer flanges *v*, the inner of which extend for a suitable distance beneath the flanges *t*, but normally 45 clear thereof, while the faces thereof extend to within a short distance of the side of the rail head. The rollers of each pair are spaced apart and between them are arranged distance pieces which may or may 50 not be elastic. In the present description, this distance piece is elastic and consists of two collars or flanges *w*, preferably of the curved form shown resting upon the spindle *u* and pressed apart by a helical spring *x* 55 coiled around the sleeve. The diameter of the flanges *w* exceeds that of the rollers, against the inner edges of which they are constantly pressed. It will be understood 60 that the flanges may thus be removed or renewed and may if desired be arranged at the outer edges of the rollers instead of the inner edges.

By the foregoing construction it will be understood that the chain track is driven 65 and the weight supported at or near both

of its longitudinal edges. The frame is allowed a certain amount of "play" laterally by the resilient or removable flanges which is of special advantage when the tractor is passing around a curve or turning 70 around in its own length. If the load is more than the predetermined power of the spring and the steering tends to move the frame toward the right, the outer projecting edge of the left hand rail head flange *t* will skate or slide against the lower edge of the frame *g*, the inwardly projecting flange *v* of the frame will skate on the side of the rail head, while the right hand resilient flange *w* will bear upon the inner projecting flange 80 of the right hand rail head flange and compress the spring. This produces a buffer action between the frame member with its rollers and the moving track preventing undue friction arising. It is also to be understood that the track framing *g* with its inwardly extending flange *v* forms a lateral 85 skate or projection which is adapted to loosely confine the flanges of the rail heads in order to prevent the track leaving the immediate vicinity of the track rollers should the configuration of the ground tend to allow the track to fall away. Lateral displacement of the track is also prevented, for should this tend to occur it will be stopped 90 by the contact of flanges *t* and *v* with the side framing *g* and the side of the rail head respectively. 95

Moreover, should one side of the track override an upstanding curb or a projection 100 on the road, for example, under the left-hand part of Fig. 2, the resultant force would be received by the edge of the adjacent roller at about *x'*, and the opposite side of the track and its rail heads will drop till the overhanging flange *t* of the rail head rides upon the flange *v*, thus supporting the track and the rail heads and preventing stress on the connecting pins *q*. 105

Having now described my invention, what I claim as new and desire to secure by Letters Patent is:—

1. A transport vehicle comprising in combination, a main vehicle frame, endless moving track mechanism supported by and driven from such frame, a vehicle frame extension the lower edge of which is adapted to engage the lower stretch of the track mechanism to prevent displacement thereof, a plurality of load supporting rollers in contact with the back of such lower stretch and supported in bearings formed in the frame extension, and means whereby such load supporting rollers are adapted to resist average stresses, but abnormal stresses 115 are resisted by the frame extension. 120

2. A transport vehicle comprising in combination, a main vehicle frame, endless moving track mechanism, means for driving such track mechanism near each end of each 130

- plate of which the endless track is formed, load supporting devices also near each end of each said plate, a vehicle frame extension, and means whereby the track under 5 abnormal circumstances is adapted to engage the side walls of the frame extension to prevent lateral displacement of the track or its leaving the immediate vicinity of the track rollers.
- 10 3. A transport vehicle comprising in combination a main vehicle frame, endless moving track mechanism supported by and driven from such frame, a vehicle frame extension the lower edge of which is adapted 15 to engage the lower stretch of the mechanism to prevent displacement thereof, a plurality of flanged load supporting rollers in contact with the back of such lower stretch and supported in bearings formed in the 20 frame extension, and means whereby such flanges are adapted to give under load without breaking and deformation.
4. A transport vehicle comprising in combination a main vehicle frame, endless moving track mechanism supported by and driven from such frame, a vehicle frame extension the lower edge of which is adapted to engage the lower stretch of the mechanism to prevent displacement thereof, a plurality 25 of load supporting rollers in contact with the back of such lower stretch and supported in bearings formed in the frame extension, a flange on each roller which is removable and renewable, and a distance piece 30 between the flanges of adjacent rollers.
5. A transport vehicle comprising in combination a main vehicle frame, a plurality of track plates, two pairs of rail heads on each track plate, a pivotal attachment be- 35 tween the rail heads of successive track plates and thus constituting an endless track, means for supporting and driving such track from said frame, a plurality of load supporting rollers in contact with the back 40 of the lower stretch of the track, a vehicle frame extension, a lateral skate or projection on the lower edge of such extension and outwardly flanged surfaces attached to the rail heads in order to prevent the track 45 leaving the immediate vicinity of the load supporting rollers should the configuration 50
- of the ground tend to allow the track to fall away.
6. A transport vehicle comprising in combination a main vehicle frame, a plurality 55 of track plates, two pairs of rail heads on each track plate, a pivotal attachment between the rail heads of successive track plates and constituting an endless track, means for supporting and driving such track 60 from said frame, a plurality of load supporting rollers in contact with the back of the lower stretch of the track, and vehicle frame extensions whose lower edges are in close proximity to and adapted to engage 65 both longitudinal edges of the endless track, to prevent lateral displacement of the track, and its sagging away from the load supporting rollers.
7. A transport vehicle comprising in combination a main vehicle frame, endless moving track mechanism supported by and driven from such frame, a plurality of load supporting rollers in contact with the back 70 of such lower stretch and supported in bearings formed in the frame extension, a flange on each roller which offers a yielding resistance to average loads, and vehicle frame extensions whose lower edges are in close proximity to and adapted to engage, both 75 longitudinal edges of the endless track and thereby resist any excess load.
8. A transport vehicle comprising in combination a main vehicle frame, endless moving track mechanism supported by and 80 driven from such frame, a vehicle frame extension the lower edge of which is adapted to engage the lower stretch of the mechanism to prevent displacement thereof, a plurality of load supporting rollers in contact 85 with the back of such lower stretch, spindles for supporting the rollers in pairs, bearings in the frame extension for such spindles, plates constituting flanges positioned against the inner edges of the members of 90 each pair of rollers and a spring positioned between the pair of plates so that they furnish a yielding resistance.

In testimony whereof I have signed my name to this specification.

WILLIAM ASHBEE TRITTON.
